UNITED STATES PATENT OFFICE.

EMIL TYDEN, OF HASTINGS, MICHIGAN.

METAL DOWEL-PIN.

SPECIFICATION forming part of Letters Patent No. 653,327, dated July 10, 1900.

Application filed November 3, 1899. Serial No. 735,665. (No model.)

To all whom it may concern:

Be it known that I, EMIL TYDEN, a citizen of the United States, residing at Hastings, Barry county, Michigan, have invented certain new and useful Improvements in Metal Dowel Pins or Tenons, which are fully set forth in the following specification, reference being had to the accompanying drawings, forming a part thereof.

10 The purpose of this invention is to provide an improved metal dowel pin or tenon adapted for use in situations in which it is essential that the pin or part performing the function of a dowel or tenon shall be permanently and 15 centrally rooted in one of the two parts to be united, so that when they are separated it shall invariably remain in that part rather than in the other. One of the most familiar situations in which this requirement occurs 20 is the case of leaves or fillers for extension-tables, which are connected to each other and to the fixed members of the table-top by tenons or dowel-pins rooted in one part and entering sockets in the adjacent part.

25 In the drawings, Figure 1 is a section of a block or board having my improved dowel-pin inserted and protruding, the pin being shown in plan view. Fig. 2 is a side elevation of the pin.

30 My improved dowel-pin is designed to be driven into the board or block in which it is to be permanently rooted, the block being first bored to form a hole whose diameter is slightly less than the diameter of the pilot- 35 point and round portion of the body of the pin. In the case of soft wood the hole will be perceptibly less in diameter than the round part of the pin; but in hard wood it will be only enough less to cause the pin to drive 40 tightly into it. A represents a block into which the pin is to be thus driven, and a the bore therein to receive the pin. The pin comprises the pilot end portion B, which is preferably cylindrical, a flattened intermediate

45 portion B', formed by striking the round rod or wire of which the pin is made between dies to flatten it in one direction and expand it in the direction at right angles to the pressure or stroke by which it is flattened, and a third 50 portion B², which constitutes the remainder

of the body of the pin from the flattened portion to the end and comprises the portion which will protrude from the block to enter the part to which the block is to be connected. The flattening of the portion B' is done in such a manner as to form a comparatively-abrupt shoulder b on each side of said flattened portion at the inner end of the pilot portion B. The dies are so shaped also as to give to said flattened portion at the sides where it extends beyond the original cylindrical outline sharpened or comparatively-acute lower edges b' b', which face downward or inward with respect to the block into which the pin is driven. Preferably these lower edge portions are slightly extended down, being produced by swaging the metal of the wire or rod off from the sides of the cylindrical pilot portion at the upper end thereof, adjacent to the flattened portion, as seen at b¹⁰ in Fig. 2. At the upper end of the flattened portion B' the formation of the dies is such as to produce quite abrupt upwardly-facing shoulders b² b², which are not acute or sharpened like the edges b', but, on the contrary, are preferably quite blunt, as illustrated; also, in distinction from the abrupt upwardly-facing shoulders b at the point of merger of the pilot end portion B in the flattened portion B', the lower end of the cylindrical body portion B² where it merges into the flattened portion B' is merged in the flattened portion of the sides of the latter, preferably by easy-sloping shoulders b³ b³. The pilot portion B of this pin is designed to be of sufficient length so that, fitting at least snugly in the hole which will be bored for it in the block, it will insure accuracy of direction to the pin as it is driven home, and it is this quality or function of the pin which causes me to name it the "pilot" portion. The purpose of the sharpened lower edges of the "fins" as the lower side portions of the flattened portion B' may be termed, is to open the grain of the wood as the pin is driven home, and that of the abrupt shoulder b at the upper end of the pilot portion and at the sides of the flattened portion is to resist the withdrawal of the pin, which it will tend to do, because the wood, having been slightly crowded out of position by the pilot, will re-

act back over the shoulders when the pilot has passed. The same purpose pertains to the abrupt and blunt shoulders b^2 b^3 at the upper end of both sides of the flattened portion 5 B', and at these points the resistance afforded by the wood opposing the withdrawal of the pin will be greater even than that which is afforded by the shoulder b , because the grain of the wood will have been spread the 10 whole thickness of the wing or fin of the pin, no part of the wood having been removed, and the reaction when the fin has passed will insure a very effective reoccupation of the space from which the wood has been displaced above 15 these abrupt shoulders. The bore made for the pin should be long enough to permit the flattened portion forming the fins described to be sunk quite a distance back of the face or edge from which the body of the pin is to 20 protrude.

As above indicated, I make this pin of wire or rod susceptible of being swaged into the shape described and of retaining sufficient stiffness after being thus swaged to be driven 25 home, as indicated, without danger of either breaking or bending in the process. It will be observed, however, that the construction tends very effectively to prevent the pin from being bent while driven home, because in 30 the first place the pilot portion encounters only a moderate amount of resistance while it is being entered in the bore and driven up to the fins, and the fins themselves, sharpened at their lower edges, obtain considerable 35 lateral support in the wood before very serious resistance is encountered from the latter. When the pin is driven home, it will be noticed that it is reinforced or supported by the wood closing snugly around its cylindrical portion at both ends of the flattened 40 portion, so that the liability to be bent at the flattened portion is very little, and this is rendered still less by the fact that the flattened portion is so firmly embedded in and engaged 45 by the wood at both edges. I have described the process of inserting this pin above as if it were to be driven into the wood with the flattened portion and fins extending in the direction of the length of the grain, so that 50 the fibers of the wood will be parted by the entrance of the fins; but it can be driven crosswise of the grain, the lower edges of the fins being designed to be sharp enough to cut their way across the grain, at least of soft 55 wood, when the situation in which it is used is such that any advantage may be obtained by inserting it in that manner.

For convenience of identifying the different parts of the pin I treat the end which 60 is first entered into the wood and toward which the acute ends of the pins point as the lower end, regarding the end toward which the abrupt shoulders face as the upper end, and in the claims it will be understood, therefore, that the words "lower" and "upper"

are merely relative terms, and indicate direction or position toward the inserted and the protruding ends, respectively.

I claim—

1. A dowel-pin made of cylindrical metal 76 rod or wire, having at the opposite ends cylindrical portions and between such cylindrical portions a portion which is flattened to a thickness less than the diameter of the cylindrical portion and widened so as to form 75 fins protruding at both sides beyond such cylindrical portions, the lower edges of such protruding fins being acute, and the upwardly-facing shoulders of the lower cylindrical portion, where the device is reduced 80 in thickness to form the flattened portion, being abrupt.

2. A dowel-pin made of cylindrical metal rod or wire having at the ends cylindrical portions, and between such cylindrical portions 85 a portion which is flattened to a thickness less than the diameter of the cylindrical portions, and widened to form fins which project at both sides beyond such cylindrical portions, the edges of the lower ends of the 90 protruding fins being acute and their upper ends constituting abrupt shoulders.

3. A dowel-pin made of cylindrical metal rod or wire having at the opposite ends cylindrical portions, and between such cylindrical portions a portion which is flattened to a thickness less than the diameter of the cylindrical portion and widened to form fins projecting at both sides beyond such cylindrical portions, the lower ends of such projecting fins being acute, their upper ends forming abrupt shoulders, the lower cylindrical portion presenting abrupt shoulders facing upward where the pin is reduced in thickness at the flattened part. 100

4. A dowel-pin made of cylindrical rod or wire, having at the opposite ends cylindrical portions, and between such cylindrical portions a portion which is flattened to a thickness less than the diameter of the cylindrical portion and widened to form fins which project at both sides beyond such cylindrical portions, such fins extending down a short distance alongside the lower cylindrical portion and terminating acutely at their lower 115 ends and abruptly at their upper ends, said lower cylindrical portion being relatively considerably extended beyond the acute terminals of the pins to constitute a pilot or steering portion for the dowel-pin. 120

5. A dowel-pin made of cylindrical metal rod or wire having cylindrical end portions, and intermediate such cylindrical portions a portion which is flattened to a thickness less than the diameter of the cylindrical portions 125 and widened to form fins which extend at both sides beyond such cylindrical portions, the lower cylindrical portion being extended suitably to adapt it to serve as a pilot or steering portion for the pin, and having abrupt, 130

upwardly-facing shoulders at opposite sides where the thickness is reduced to form the flattened portion, the upper cylindrical portion having long, sloping, downwardly-facing
5 shoulders where said reduction in thickness occurs.

In testimony whereof I have hereunto set

my hand, in the presence of two witnesses, at Chicago, Illinois, this 30th day of October, 1899.

EMIL TYDEN.
